BRADLEY & WILHELM CUFF LINKS

UNITED STATES PATENT OFFICE.

JOSEF PEJCHAR, OF BROOKLYN, NEW YORK.

CUFF-LINK.

1,258,449.

Specification of Letters Patent.

Patented Mar. 5, 1918.

Application filed June 15, 1916. Serial No. 103,772.

To all whom it may concern:

Be it known that I, JOSEF PEJCHAR, a citizen of the United States, and resident of the borough of Brooklyn, county of Kings, 5 city and State of New York, have invented certain new and useful Improvements in Cuff-Links, of which the following is a specification.

My invention relates to cuff-links, and has 10 for its object to provide a simple and inexpensive made yet very efficient and readily applied cuff-link of ornamental appearance. My improved cuff-link comprises two heads and a connecting shank so arranged that its ends will be visible when the link is worn, said ends also coöperating with the adjacent portions of the heads in the manner fully set forth hereinafter, to clamp the material of the cuff and thus hold 15 the link in position firmly. Other features of my invention will appear from the description following hereinafter, and the appended claim defines the scope of the invention.

Reference is to be had to the accompanying drawings, in which Figure 1 is a face view of a blank from which one form of link embodying my invention may be made; Fig. 2 is a face view of the link made from 20 said blank, looking in the direction of the arrow 2 in Fig. 3; Fig. 3 is an edge view of such link, indicating its position on the cuff; Figs. 4 and 5 are respectively a side elevation and a section on line 5—5 of Fig. 4, 25 showing another form of my invention; Figs. 6 and 7 are a face view or top view and an edge view respectively of a third form of my invention; Figs. 8, 10, and 12 are side elevations of three further forms 30 of my invention; and Figs. 9, 11 and 13 are corresponding edge views.

The cuff-link illustrated by Figs. 1, 2, and 3 is shown as made from a single piece or blank of sheet-metal, which blank is of rectangular shape (Fig. 1) and provided with 45 two T-shaped slits *a*, *a'* the long members of which, *a*, extend parallel with the longitudinal edges of the rectangular blank and at equal distances therefrom, while the short members *a'*, perpendicular to the slit members *a*, extend at the central portion of the blank, from the longitudinal edges thereof to said slit members *a*. These slits form the blank into a connecting member or shank A 50 and two U-shaped members or heads, and a simple bending operation will bring this

blank into the form shown in Figs. 2 and 3, the two heads B being flat and in converging planes, while the connecting shank A would form an arc or bow having its convexity on the side toward which the heads converge. The ends of the connecting shank are tangential to the said converging planes of the heads, or approximately so, and a small angle is formed between the inner 60 surface of each head and the adjacent surface on the end portion of the connecting shank, as shown at *b*, and this angle forms a wedging pocket for the portion of the cuff at the buttonhole, see Fig. 3, so that when 65 the link is worn, it will grip the edge of the cuff buttonhole by a wedge-action, and thus be prevented from shifting or becoming loose. Of course the edges of the cuff-link members will be preferably rounded by 70 filling or otherwise. It will be observed that the U-shaped heads have openings adjacent to their points of connection with the shank A and that the ends of the connecting member or shank A will be visible through these 75 openings, when the link is worn, said ends of the connecting shank being flush with the heads, and exposed. The visibility of the ends of the connecting shank adds a characteristic and ornamental feature to the appearance of the cuff-link.

These features of the visibility of the ends of the connecting member or shank through the openings formed in the heads, and of the wedging action exerted by said ends in 80 conjunction with the adjacent portions of the heads, are present also in the other forms of my invention, shown in Figs. 4 to 13, which I will now proceed to describe:

The construction shown in Figs. 4 and 5 is 85 very similar to that first described, differing therefrom partly as regards the proportions of the parts, but more particularly in the following respects: First, instead of leaving the heads U-shaped, I complete them to 90 square or rectangular outline by soldering or otherwise fastening small pieces of metal, as at C, which may be done in such a way as to leave the joints invisible, so that the head will appear to be made of a single 95 piece. Second, an ornamental U-shaped slit *c* has been made in the head, the shank A' being somewhat narrower relatively to the head B' than in the construction first described.

Figs. 6 and 7 show how a cuff-link embodying my invention may be made from a

continuous piece of wire. This is bent to form two contiguous portions A² forming the connecting shank, and two rectangular frame-like portions B² forming the heads of the link. The ends of the wire are preferably soldered together with a concealed joint.

In Figs. 8 and 9 the two heads B² are of similar shape, but of different sizes, and 10 simulate a ribbon-bow, and the connecting shank A², which may be integral with said heads, has its ends extended over the central portions of the heads so that said ends are readily visible when the link is worn. If 15 desired, the connecting shank A² may be formed with a projection or ridge d adapted to extend into the buttonhole of the cuff to more securely hold the link against turning, although this projection is really not necessary, and I prefer to omit it. If desired, such a projection may be used in 20 connection with the other forms of my invention.

Figs. 10 and 11 show a link with two like 25 heads B³ made in the shape of a fleur-de-lis, and the connecting shank A³ is bent in substantially the same manner as described above, so as to form an acute angle b to clamp the cuff at the edge of the buttonhole. 30 This form of my invention also is readily made of a single piece of metal.

In the form of my invention represented in Figs. 12 and 13, both heads are in the nature of frames with central openings, one

of them, B⁴, being oval, while the other, 35 B⁵, is square. The connecting shank A⁴, arranged according to the general principles explained above, has its ends passed into and through the apertured heads, and in front of the outer surface of each head, these 40 ends presenting the appearance of tongues on buckles, the heads themselves appearing as buckles. The effect may be enhanced by making the tongue or shank A⁴ of a material contrasting with that of the heads; 45 for instance, the shank may be made of silver or silver-plated, and the heads of gold or gold-plated.

The improved cuff-link, in any of the forms described above, is readily manufactured, lends itself to pleasing ornamentation, is easily slipped into and out of the cuff buttonhole, and grips the edge of the buttonhole firmly so that the link will not be liable to slip or turn in the buttonhole. 50

Various modifications may be made without departing from the nature of my invention as defined in the appended claim.

I claim as my invention:

A cuff-link having two heads and a member or shank connecting them, the heads having openings adjacent to their points of connection with said member, whereby the ends of said member are visible from the outside when the link is worn on the cuff. 60 65

In testimony whereof, I have signed this specification.

JOSEF PEJCHAR.
